[57] **CLAIM**

The ornamental design for a van roof for customized conversion vans, as shown and described.

DESCRIPTION

FIG. 1 is a perspective view of the top, front and one side of a van roof for customized conversion vans showing my new design;

FIG. 2 is a side elevation view thereof, the opposite side being a mirror image of that shown;

FIG. 3 is a front elevation view thereof;

FIG. 4 is a rear elevation view thereof; and

FIG. 5 is a bottom plan view thereof.

FIG 2
